CLEANING APPARATUS FOR RUGS, CARPETS, AND OTHER HEAVY FABRICS

Application filed February 20, 1930. Serial No. 429,968.

The present invention pertains to apparatus for cleaning heavy fabrics such as rugs and carpets. This device may also be used in the cleaning of heavy portieres and the like.

Among the objects of this invention are to provide an apparatus for the purpose indicated which will be simple in its construction and inexpensive to manufacture; to provide an apparatus of the character indicated which will be easily operated and will be effective for its intended purpose; to provide an apparatus which will be more effective in the cleaning of fabrics than are the structures heretofore manufactured; to provide an apparatus of the character indicated which will, after being put into operation, be entirely automatic in the cleaning of the fabrics; to provide an apparatus of the character indicated in which the fabric supporting drum will not be directly driven from the power unit but will be indirectly driven by the beater elements; to provide an apparatus of the character indicated having means for causing air circulation through the interior of the rug during the cleaning operation; and such further objects, advantages and capabilities as will hereafter appear and as are inherent in the construction disclosed.

My invention further resides in the combination, construction and arrangement of parts illustrated in the accompanying drawings and, while I have shown therein what is now considered the preferred embodiment of this invention, I desire the same to be understood as illustrative only and not to be interpreted in a limiting sense.

In the drawings annexed hereto and forming a part hereof, Fig. 1 is a longitudinal, vertical section, substantially centrally through the apparatus, showing a mechanism in accordance with my present invention; Fig. 2 is a horizontal sectional plan view substantially along the plane indicated by the line 2-2, Fig. 1; Fig. 3 is an elevation on a larger scale than that shown in Figs. 1 and 2 of the drawings of the drum upon which the fabric to be cleaned is mounted; Fig. 4 is a transverse section through the construction as illustrated in Fig. 3, substantial-

ly along the plane indicated by the line 4-4 of that figure; Fig. 5 is a transverse section substantially along the plane indicated by the line 5-5, Fig. 3; Fig. 6 is a plan view of a modified form of this construction illustrating the use of a plurality of drums for the holding of the fabrics so that there can be continuous operation of the device, one rug or carpet being cleaned while two others are being cleaned.

In the past the most common method of cleaning rugs has been to spread them out on grass and beat them by hand or hang them over a rope or other support and beat them. Another method of cleaning certain fabrics is illustrated by Roberts' Patent No. 1,231,940 in which the rug or carpet is moved about a horizontal axis and beaten on the inside to jar the dust loose on the outside. None of these methods have proven entirely satisfactory and I have therefore developed the present method and means for cleaning rugs, carpets and other like heavy fabrics in which quantities of dust accumulate. An important part of this invention is the mounting of the fabric in a vertical position so that dirt jarred loose therefrom may move in a vertical direction away from the fabric. Another important part of this invention is the provision of means for forcing an air current through the cylinder upon which the fabric is mounted so as to blow floating dust out of the interior of the cylinder, replacing the dust laden air with fresh clean air from outside. Another important element of this invention is the striking of the fabric by beater elements in such a manner that the blow will be sharp and quick, thus jolting the dust and dirt loose.

Another important idea is that of being able to move the cylinder from a vertical to a horizontal position in which the fabric can be easily applied to or removed from the drum upon which it is carried when being cleaned. Another important idea is the absolute simplicity of the entire mechanism. Another important idea is that of being able to clean a plurality of fabrics at one time, making the operation a continuous one, the person operating the machine being able to remove a cleaned fabric and substitute another to be

cleaned without the necessity of stopping the operation of the machine.

Referring more in detail to the annexed drawings, the supporting frame for the machine is denoted by the numeral 1 and the overhead support by the numeral 2. This may be and preferably is an overhead portion of a building in which the device is housed. Any suitable motive means 3, such as electric or gasoline motor may be provided. Between this and the shaft 5 of the beater element 6 are suitable transmitting means 4. From this it will be seen that as the driving means 3 operates, the shaft 5 will be caused to rotate on its vertical axis in its bearings 7 and 8. In order to reduce power losses by reason of friction, both thrust and lateral bearings of suitable type may be provided in the bearing 7. Preferably, such will consist of ball 20 of roller bearings. While the bearing 8 is shown as mounted upon a framework 9 supported from the overhead support 2, it will be understood that this bearing may be mounted directly upon the overhead support 25 if desired.

Frame elements 10 are shown as connected with the frame member 1 and there is shown between these frame elements and below the fabric supporting drum a pan 11 containing water or the like for the collection of dust and dirt passing downwardly through the cylinder during the cleaning operation. Resting upon the frame elements 10 is a supporting member 12 which, as shown in Figs. 30 1 and 2, is hinged to one of the members 10 so that when the cylinder is lowered into the dotted line position shown in Fig. 1 the same will be held upwardly away from the floor. Fixedly secured to the supporting member 12 35 is a shaft 13 which is provided with an adjustable supporting ring 14 which may be secured in position in any desired manner as, for example, by means of a set screw. Resting upon this collar 14 is a bearing element 40 15 constituting part of a thrust bearing for supporting the weight of the cylinder and rug, the same making it possible for the supporting cylinder to rotate readily about the shaft 13. Near its upper end, the shaft 13 45 is provided with a collar 16 similar to collar 14 and this is adjustably held in place in the same manner as collar 14. Upon the collar 16 is a thrust bearing 17, similar to the one described above, whose purpose is to sustain 50 a portion of the weight of the device during the operation of the machine. The shaft 13 passes through bearing blocks 18 suitably secured in the end elements of the drum or cylinder. It will therefore be seen that the 55 drum is supported in a substantially frictionless manner and that the same may turn easily under the influence of an applied force. The drum comprises a pair of end elements 19 connected by longitudinal ribs 20 and 60 coiled springs 21. For convenience, the low-

er member of the drum or cylinder is denoted by the numeral 19a. Each of these members is made up of four sections, each of which has two substantially radial arms arranged at substantially 90° from each other, the outer 70 extremities of the arms being connected by quadrants. Adjacent radial arms are secured together in any suitable manner as by rivets 22. The upper radial arms 23 have blades 24 inserted between them and held in place by the fastening means 22 which pass through openings in an edge of each blade. As indicated in Fig. 1 the blades are bent at an angle so that as the drum is rotated these blades will act as a fan to drive air downwardly through the interior of the drum. An inwardly inclined flange 25 is formed on an edge of the ring 19a and this tends to deflect the air inwardly toward the shaft 13 as it is forced downwardly by the blades 24. The air passing in this way has a tendency to strike the water in the pan 11 and drop its dust there so that there will not be so much passing outwardly into the air of the room. Any suitable number of coiled springs 21 may 80 connect the heads 19 and 19a to serve as suitable supporting means for the rug when it is being mounted upon the drum in the horizontal dotted line position shown in Fig. 1 or at any other time when such support may be 85 needed. As indicated at 26, the longitudinal bars or ribs 20 are connected in pairs to assist in making the structure rigid. Attention is called to the fact that one pair of these bars do not have any connecting means 90 between the two heads 19 and 19a. Also, these bars are held in spaced relation so as to leave room for a portion of the rug to extend inwardly between them. A plurality of 95 hooks 27 are secured to or formed along an edge of one of these bars, as shown in Fig. 4, to permit the attachment of an edge of the rug. This attachment may either be made by hooking the edge of the rug directly upon the 100 hooks 27 or by securing suitable loops to an 105 edge of the rug in positions to engage the hooks. The rug is indicated in Fig. 4 by the numeral 28 and the part thereof which exceeds that required to go around the drum is 110 indicated by the numeral 29. This latter extends into the interior of the drum. If the 115 length of the rug is greater than the circumference of the drum, as illustrated in Fig. 4, it will be necessary to remove the rug from the drum, after it has been cleaned in one 120 position, and then turn it end for end so that the portion 29 may be connected to the hooks 27 and the other end inserted into the interior of the drum. In this way, the entire rug 125 may be cleaned. Inasmuch as the apparatus may be made in any desired size, it will be understood that it can be made large enough to accommodate large sized rugs. Since the most common size of rug is 9 ft. x 12 ft., most 130 of these machines will be made to accommo-

date that size, though they can be made to take larger sized rugs, if desired. If it is desired to clean runners, two or more of these may be placed side by side around the drum.

5 In this way, several runners and small rugs may be cleaned at one time upon the same drum.

When the drum is in horizontal position, as illustrated in Fig. 1, one end of the shaft 13 is held elevated by the supporting member 12 while the other end thereof is supported by the support 30. It will therefore be understood that the drum may be turned about the shaft 13 as an axis while removing a rug therefrom or placing one thereon. When a rug has been put in place as indicated in Figs. 3 and 4, the straps 31 are put around the rug and the fasteners 32 are fastened to hold the rug in place. The cylinder is then ready to be raised to the full line position shown in Fig. 1 and this is done by pulling on the rope 33 until the cylinder is raised part way. This rope passes through the blocks 33a and 33b and therefore gives additional power in the lifting of the cylinder and rug when this is in the position where it is hardest to lift. After the cylinder or drum has been raised part way, the operator then pulls on the rope 34 which pulls the cylinder up through the intermediate dotted position shown in Fig. 1 and into the full line position shown in this figure. A weight 35 is provided to maintain the rope 34 in a tight position at all times. However, this is not necessary and may be omitted, if desired. A bracket 37 secured to a cross bar 38 on the frame 9 serves to hold the shaft 13 against that frame and prevents lateral swinging or tipping of the shaft. The rope 34, passing over the pulley 39 tends to hold the shaft 13 in place between the arm 37 and the frame 9. However, this is really unnecessary in view of the fact that the weight of the drum and rug has enough tendency in this direction so that 45 no particular stress needs to be put upon the rope 34 to hold the shaft in place.

When the drum is in the full line position shown in Fig. 1 and has a rug mounted thereon as shown in Fig. 3, the apparatus is ready 50 to operate and the motive means 3 is then started. Through the transmission means 4, this causes the shaft 5 to rotate. Any suitable number of beater units 40 may be attached to the shaft 5. I prefer to have four 55 arms arranged radially in a plane about the shaft 5 and then have such arms spaced suitable distances along the shaft. I prefer to form these arms of straps, the ends of which are passed through chain links 41 and then doubled back and secured by a rivet or any other suitable means. This makes the ends 60 of these beater arms heavy so that as the shaft 5 is rotated rapidly the links 41 will strike a sharp blow upon the rug. These 65 arms are just short enough so that the links

41 cannot damage the fabric by pinching it between the links and the longitudinal bars 20. Normally, the rug hangs loosely enough on the drum so that as the beater unit 6 rotates, the links 41 strike the surface of the rug and start the drum to rotating. As it rotates, the rug is expanded somewhat by centrifugal force and somewhat by the air which is forced downwardly through the cylinder by the vanes 24. It then bulges outwardly somewhat in the manner shown in Fig. 3. In a short time, the drum will be rotating nearly as rapidly as the beater element itself and each time a set of arms comes around, a blow will be struck across substantially the whole width of the rug. Because of the fact that the beater is rotating at high speed, the blows will be short and sharp and have a maximum tendency to jar the dust loose. The current of air passing down through the drum carries the dust from the inside of the rug downwardly and out of the rug so that there is no tendency for it to settle again upon the surface of the rug.

The structure shown in Fig. 6 is the same as that shown in the other figures except that there are a plurality of the rug carrying drums arranged around the beater unit so that one or more of these may be used at a time. In sequence operations, one drum may be loaded and then put into operating position and the cleaning operation partly carried out while the next drum is being loaded. When this is ready, it is raised into operating position and the beater then acts upon this as well as upon the one which was first set into operation. The beating of these two rugs may continue while the third cylinder is being loaded and being put into operation. When this is started, the rug on the first cylinder may be sufficiently clean so that the cylinder may be tipped over into loading and unloading position. If a part of the rug was inside of the drum so that it did not get cleaned, it may be removed from the drum and turned end for end and fastened in place. Now, if the drum be raised to operating position, the cleaning operation will be continued and completed. The drum may now be let down and the rug removed and, if there is another rug ready to take its place, this may be mounted upon the drum and raised into operating position. It will be seen from the foregoing that the entire work of the operator is that of loading and unloading the cylinders, raising them into operating position and lowering them therefrom, and, when necessary, starting or stopping the operating motor. As a source of power, I have found a kerosene motor the most economical. It is of course understood that the specific description of structure and method set forth above may be departed from without departing from the spirit of my invention as

set forth in this specification and the appended claims.

Having now described my invention, I claim:

- 5 1. In a cleaning machine for heavy fabrics, a supporting frame, a substantially vertically extending axle on the frame, a vertically extending drum mounted on the axle to rotate thereabout, and a rotatable beater unit having beating elements to strike a fabric carried by the drum, the ends of the beating elements, when the beater unit is rotated, passing close to but out of contact with the drum.
- 10 2. In a fabric cleaning machine, the combination of supporting means, a supporting unit pivotally connected thereto to be swung in a substantially vertical direction, an axle rigidly carried by said supporting unit, a drum mounted on said axle for rotation thereabout when the axle is in either vertical or horizontal position, and means mounted adjacent the drum when the drum is in a vertical position for beating a fabric carried by the drum.
- 15 3. In a fabric cleaning machine, a supporting member pivotally mounted on a horizontal axis to be swung in a substantially vertical direction, a fixed axle carried thereby and swinging therewith in a substantially vertical plane, a drum mounted on said axle to rotate around the same, a fabric beating unit located adjacent the drum when the latter is in a substantially vertical position, and means for causing the beating unit to beat a fabric on the drum.
- 20 4. In a fabric cleaning machine, a support, a supporting element pivoted thereon to swing from a substantially horizontal to a substantially vertical position, an axle mounted on said supporting element to be normally fixed with relation to the supporting element, a second supporting element fixed with relation to said support at a distance from the first named supporting element, and a drum rotatably mounted on said axle, the axle, when turned into engagement with the second named supporting element, supporting the drum out of contact with the support and free to rotate about said axle, in combination with a beater mounted adjacent the position occupied by the drum when turned into a vertical position, said beater cooperating with said drum in the cleaning of fabrics.
- 25 5. In a fabric beating machine, a substantially vertically extending axle, a drum on the axle and capable of rotating about same, means on the axle supporting the drum for ready rotation thereon, beating means adjacent the drum for rotation in proximity thereto but out of contact therewith, and means for operating the beating means.
- 30 6. In a beating machine, a pivotally mounted axle normally occupying a substan-

tially vertical position when the machine is in use, said axle being pivotally mounted to be turned into and supported in a substantially horizontal position, an open-work cylinder loosely mounted on the axle for free rotation thereabout, a beater unit mounted for rotation adjacent the cylinder when the latter is in operating position, and means for operating said last mentioned means.

7. In a rug cleaning machine, an axle normally occupying a substantially vertical position, a cylinder mounted on said axle and capable of rotation thereabout, means for tipping the axle and cylinder into a substantially horizontal position with the cylinder supported free of obstruction for substantially free rotation upon the axle, and means for lowering the cylinder into substantially horizontal position and raising it into substantially vertical position.

8. A structure as defined by claim 7 having a beating unit in proximity to the cylinder when the latter is in elevated position, and means for rotating the beater unit close to but out of contact with the cylinder.

9. In a structure for the purpose indicated, a drum mounted to be rotated about a substantially vertical axis, means for supporting the drum in a vertical position, said drum being capable of free rotation when in an upright position and being pivotally mounted to be turned into a substantially horizontal position and, in that position, of having substantially free rotation, and beater means for cooperation with the drum in its upright position.

10. A structure as defined by claim 7 in which the cylinder is provided at its upper end with vanes for causing a current of air to pass downwardly through the cylinder when it is being rotated about its vertical axis.

11. A structure as defined by claim 7 in which the lower end of the cylinder is provided with an inwardly and downwardly inclined baffle to direct a current of air passing through the cylinder inwardly toward the axis and downwardly, said apparatus having means for directing a current of air downwardly therethrough.

12. A structure as defined by claim 7 having means in connection with the cylinder for forcing air downwardly therethrough and means adjacent the bottom of the cylinder for collecting dust from the dust laden air passing downwardly through the cylinder.

13. In a structure for the purpose indicated, a support normally occupying a substantially horizontal position, an axle carried by said support and normally occupying a substantially vertical position when the support occupies a horizontal position, a drum mounted on said axle for free rotation thereabout, said drum having means in con-

nection therewith for causing a downward flow of air through the drum when the machine is operated.

In witness whereof, I hereunto subscribe
5 my name to this specification.
